THREAD GUIDE

Francis P. Tamburro, Ozone Park, N. Y., assignor
to Wilcox & Gibbs Sewing Machine Company,
New York, N. Y., a corporation of New York

Application November 6, 1943, Serial No. 509,208

5 Claims. (Cl. 112—218)

1

This invention relates to sewing machines, and more particularly to improved means for guiding the thread as it advances along an angular path toward the needle.

An object of this invention is to provide a thread guide which may be used for a plurality of threads in a multineedle machine and which, besides being easy to make and install, is easily engaged by the threads, and, when properly engaged, holds the threads to itself even though the paths of the threads be outwardly and away from the guide.

The thread guide of the present invention, in the form illustrated herein as exemplary thereof, comprises a plate adapted to be secured to the machine frame and having a plurality of fingers which project from it obliquely and which are bent or rolled over toward the plate to lie over the surface of the plate and form skewed loops. The ends of the fingers overlap, without touching, the edge of the plate and the base of the adjacent finger, thus forming eyes having slanting openings through which the stretches of threads may be passed. Thus, with the thread guide of the present invention, it is not necessary to use closed loops or eyes through which the thread must be passed end-first.

In using the thread guide of the present invention, the plate is so mounted that the fingers slant away from the direction in which the thread is to be turned.

Other features and advantages will hereinafter appear.

In the accompanying drawing which illustrates one form of this invention, that at present preferred—

Figure 1 is a front view showing the thread guide of the present invention located between the needle thread take-up member and the needle thread lower guide from which the thread passes to the needle bar.

Fig. 2 is a partial transverse sectional view taken on the line 2—2 of Fig. 1, showing the angular path of the thread when viewed from the side, and showing the relationship of the thread guide of the present invention to the needle thread lower guide and the needle thread take-up mechanism.

Fig. 3 is a front view of the thread guide plate of the present invention.

Fig. 4 is a transverse view of the thread guide.

Fig. 5 is a top plan view of the thread guide.

Fig. 6 is a plan view of the blank of the thread guide before the slanting fingers are bent back upon the plate.

2

In sewing machines, the guiding of the thread to the needle bar is a comparatively simple matter where the path of the thread forms such an angle that the guiding means may be placed on the inside of the angle, for in such situations it is merely necessary to provide slots in a plate into which the thread may be slid so as to rest at the bottom of the slot. In situations where the thread forms an angle and it is not convenient to place the guiding means on the inside of the angle, the matter of guiding the thread has been a serious problem. Thread guides for such portions of the path of the thread may, of course, consist of closed loops or eyes, but in such cases it is necessary to pass the end of the thread through the eye.

In a multineedle machine, besides being inconvenient, the closed eye guiding means is rather expensive to make, since each eye must be made separately and be separately fastened to a plate. Another solution of the problem is to provide a guide having spring-closed openings through which the thread may be forced, and, when once placed in the guide, is prevented from pulling out by the spring. But, this kind of guide is quite expensive to make, and since it involves moving parts is liable to get out of order.

As will appear below, the present invention provides a simple and economically made plate which embodies the advantages of closed eyes and yet which may be threaded without manipulating the end of the thread, does not have any moving parts, and securely holds the thread from escaping its control.

As shown in the accompanying drawing, the thread guide 10 of the present invention comprises a plate 11 having a mounting hole 12 adapted to receive a screw 13 and a locating hole 14 adapted to receive a pin 15 fixed on a flat 16 on the machine frame 17. The plate 11 is blanked out from a piece of sheet metal so as to have the shape shown in Fig. 6. The blank is made so as to have a plurality of fingers 18 extending obliquely with relation to the longitudinal edge 19 of the plate. The blank 11 is then worked so that the fingers 18 are bent as a group on an axis parallel to the longitudinal axis of the plate so that each finger has a hook portion 20, skewed so that the end of each overlies the plate 11, and when viewed in plan overlies the base 21 of the adjacent finger. The end finger 18 overlies a projection 22 on the end of the plate.

When the thread guide of the present invention is mounted on the outside of the path of the thread as shown in Fig. 2, the threads are

held in the loops formed by the hooks 20 and are caused to follow the paths defined by the hooks both in a vertical plane as shown in Fig. 2, and in a horizontal plane as shown in Fig. 1. Any tendency of the threads to fall away from the hook by simply dropping down is prevented by the skewed arrangement of the finger, for, in order to be released from the hook, the thread must not only drop down but also move to the side, and since there is no tendency for the thread to have this compound movement it is trapped against escaping from between the fingers.

In a situation in which the plate 10 is used in the form of the invention illustrated in the accompanying drawing, the threads 23 (see Fig. 2) pass over tensioning devices 24, then through an upper guide 25, and downwardly in front of the needle thread take-up members 26, through guide 10 of the present invention and then laterally to the lower needle thread guide 27, and finally to the bar 28. To pass the thread over the guide plate 10, it is merely necessary to place the loop of the thread formed between the guide 25 and the guide 27 over the end of its cooperating finger 18. The thread when tautened will then ride up on the hook 20 and be confined in the loop of the hook, for the finger is skewed in a direction normal to the path of the thread.

The needle guide of the present invention is particularly advantageous when used in combination with rotary takeup means such as the take-up elements 26, since, should any slack be formed in the thread as the take-up elements move away from the part of the thread between the guide 25 and the guide 10, it will not slip off the hook finger 18 because of the fact that the latter is skewed away from the path of the thread.

In order to provide smooth edges over which the thread rides, the fingers 18 are wedged to remove sharp corners as shown in Fig. 6 and the

walls of the spaces between the fingers are polished before the fingers are bent.

Variations and modifications may be made within the scope of this invention and portions of the improvements may be used without others.

I claim:

1. A thread guide comprising a plate having a plurality of inclined fingers projecting from one edge thereof, said fingers being bent out of the plane of the plate and skewed toward the plate and forming thread eyes having slanting thread receiving openings between them.

2. A thread guide comprising a plate having a plurality of integral inclined fingers projecting from one edge thereof, said fingers being bent out of the plane of the plate and skewed toward the plate and forming thread eyes having slanting thread receiving openings between them, the edges of the fingers being rounded off to provide a smooth guide surface for the thread.

3. A thread guide comprising a plate having a plurality of inclined fingers projecting from one edge thereof, said fingers being bent out of the plane of the plate and extending in a loop toward the plate and forming slantingly open eyes.

4. A thread guide for controlling the angular path of a plurality of threads and located outside the angle of said path comprising a plurality of hooks skewed so that the end of one hook overlies in spaced relation the base of another hook.

5. A thread guide comprising a plate stamped out of sheet metal to form a plurality of obliquely disposed fingers along one end of the plate, said fingers being bent out of the plane of the plate and back toward the plate to form a plurality of hooks skewed to present guiding edges normal to the direction of travel of the threads.

FRANCIS P. TAMBURRO.
